(57) **CLAIM**

The ornamental design for a modular furniture adapter faceplate, as shown and described.

DESCRIPTION

FIG. 1 is a top perspective view of a modular furniture adapter faceplate showing my new design;

FIG. 2 is a bottom perspective view thereof;
FIG. 3 is a front elevational view thereof;
FIG. 4 is a back elevational view thereof;
FIG. 5 is a top plan view thereof;
FIG. 6 is a bottom plan view thereof;
FIG. 7 is a right elevational side view thereof, the left elevational side view being a mirror image;
FIG. 8 is a top perspective view of a second embodiment of a modular furniture adapter faceplate showing my new design;
FIG. 9 is a bottom perspective view of the second embodiment thereof;
FIG. 10 is a front elevational view of the second embodiment thereof;
FIG. 11 is a back elevational view of the second embodiment thereof;
FIG. 12 is a top plan view of the second embodiment thereof;
FIG. 13 is a bottom plan view of the second embodiment thereof;
FIG. 14 is a right elevational side view of the second embodiment thereof, the left elevational side view being a mirror image;
FIG. 15 is a top perspective view of a third embodiment of a modular furniture adapter faceplate showing my new design;
FIG. 16 is a bottom perspective view of the third embodiment thereof;
FIG. 17 is a front elevational view of the third embodiment thereof;
FIG. 18 is a back elevational view of the third embodiment thereof;
FIG. 19 is a top plan view of the third embodiment thereof;
FIG. 20 is a bottom plan view of the third embodiment thereof; and,
FIG. 21 is a right elevational side view of the third embodiment thereof, the left elevational side view being a mirror image.
FIGS. 17-21 are shown on a reduced scale in relation to FIGS. 15 and 16.
The adapter faceplates mount to openings in modular furniture to hold telecommunications cable connections.

1 Claim, 12 Drawing Sheets
